UNITED STATES PATENT OFFICE.

WILLIAM M. MIKELL, OF BLACKSHEAR, GEORGIA, ASSIGNOR OF ONE-HALF TO MIKELL, NOBLES AND COMPANY, OF BLACKSHEAR, GEORGIA.

FISH-STRINGER.

1,212,087.

Specification of Letters Patent.

Patented Jan. 9, 1917.

Application filed July 11, 1916. Serial No. 108,659.

To all whom it may concern:

Be it known that I, WILLIAM M. MIKELL, a citizen of the United States, residing at Blackshear, in the county of Pierce and State of Georgia, have invented new and useful Improvements in Fish-Stringers, of which the following is a specification.

This invention relates to fish stringers or carriers for supporting a number of fish and 10 it has for its object to provide a device of this character having means for securely retaining the fish upon the carrier to prevent accidental removal of the same.

Another object of this invention is to provide a device of this character which will 15 conveniently support a number of fish thereupon whereby the same may be readily transported from place to place.

Another object of this invention is to provide a device of this character which contains the novel features of simplicity, durability and efficiency, and furthermore a device which may be manufactured at a nominal cost.

25 Other objects of the invention will appear as the specification is read in connection with the accompanying drawings, in which:—

Figure 1 is a side elevation of the device constructed in accordance with my invention showing one of the stringing members in released position; Fig. 2 is a horizontal section taken on the line 2—2 of Fig. 1.

Referring to the drawings in detail, my invention comprises a frame generally indicated as at A which is formed in this instance of a single piece of resilient wire bent intermediate its ends to provide the loop handle 1. The ends of the handle are intertwined upon themselves to provide the shank 2, the ends of the shank being bent at right angles as at 3 to provide the angular offset portion 4. The ends of the offset portions 4 are bent downwardly at right angles to the portions to provide the parallel rigid members 5 of the stringing elements generally indicated as at B. To hold the rigid members 5 in rigid spaced parallel positions, I provide the same with a plate 6, preferably arranged adjacent the juncture of the rigid members and the offset portions, the same having its opposite extremities secured to the rigid members 5 whereby the members will be held in parallel spaced relation. The free ends of each of the rigid members 5

are bent upon themselves in substantially U-shaped formation to provide the resilient movable members 7 of the stringing elements B, the free ends of the latter being flared outwardly as at 8 and terminating at a point above the upper end of the rigid members. 60 Twisted about the shank 2 is the intermediate portion 9 of a rigid wire C, the opposite ends of the wire C extending at right angles from the opposite sides of the shank 2 and terminating in reversely disposed return 65 bends 10 to provide the keepers 11. The free ends of each of the keepers 11 are bent inwardly as at 12 and are adapted to normally lie in spaced relation to the shank portion of the wire C whereby the ready 70 insertion of the removable members 7 will be permitted.

It will be evident from the foregoing that the free ends of the removable members are adapted to lie within the keepers 11, it being understood that owing to the inherent resiliency of the material of which the removable members are formed, it will be necessary to contract or compress the members 7 toward the rigid members 5 whereby they 80 may be inserted into the keepers remaining within the keepers under their tension as will be understood.

In operation, the free ends of the removable members 7 are removed from the 85 keepers 11 whereby the fish may be strung upon both the movable and the rigid members whereupon the removable members will be moved so as to have their free ends lie within the keepers 11 thus locking the fish 90 upon the stringing elements and preventing the accidental removal of the same. It will thus be seen that I have provided a simple and efficient means for supporting a plurality of fish and locking them upon the stringing elements so that the device may be suspended within the water without the accidental loss of the fish and furthermore that the fish may be conveniently carried by the handle 1 to permit the ready transportation 100 of the fish from place to place.

It is thought from the foregoing taken in connection with the accompanying drawings, that the construction and operation of my device will be apparent to those skilled 105 in the art without further description, that minor changes in the size, shape, proportion and minor details of construction may be

made without departing from the spirit and scope of the appended claims.

What I claim is:—

1. A fish stringer comprising a single length of resilient wire bent intermediate its ends to provide a handle, the ends of the handle being twisted upon themselves to provide a shank, the free ends of the shank being extended at right angles to provide the offset portions, the free ends of the offset portions being extended to provide the parallel spaced rigid members, a plate connecting the members, the free ends of the rigid members being extended to provide the movable members, and a rigid wire having its intermediate portion twisted about said shank, the opposite ends thereof terminating in reversely disposed keepers, said keepers

receiving the free ends of the movable members.

20

2. A fish stringer comprising a single length of resilient wire bent intermediate its ends to provide a handle, the ends of the handle being twisted upon themselves to provide a shank, the free ends of the shank being extended at right angles to provide the offset portions, parallel spaced rigid members formed integral with the offset portions, the free ends of the rigid members being bent upon themselves to provide the movable members, and reversely disposed keepers formed on the shank of said handle and detachably receiving the free ends of the movable members.

25

In testimony whereof I affix my signature. 30
WILLIAM M. MIKELL.
